Joseph J. Neff, South Euclid, Ohio, assignor to
Jack & Heintz Precision Industries, Inc., Cleve-
land, Ohio, a corporation of Delaware

Application September 6, 1946, Serial No. 133,090

Term of patent 3½ years

(Cl. D52—1)

To all whom it may concern:

Be it known that I, Joseph J. Neff, a citizen of the United States, residing at South Euclid, in the county of Cuyahoga and State of Ohio, have invented a new, original, and ornamental Design for an Inner Race Gauge, of which the following is a specification, reference being had to the accompanying drawing, forming a part thereof.

Figure 1 is a view in perspective of an inner race gauge showing my new design, and

Figure 2 is a top plan view of an inner race gauge.

I claim:

The ornamental design for an inner race gauge, substantially as shown.

JOSEPH J. NEFF.
